UNITED STATES PATENT OFFICE

FLOYD C. KING, OF BIRMINGHAM, MICHIGAN, ASSIGNOR TO GUARDIAN TRUST COMPANY, OF DETROIT, MICHIGAN, A CORPORATION OF MICHIGAN, TRUSTEE

PUNCH

Application filed June 10, 1929. Serial No. 369,905.

This invention relates generally to punches and refers more particularly to the type of punch set forth in my application filed February 11, 1929, bearing Serial No. 339,145.

5 One of the essential objects of the invention is to provide a punch that will be effectively held in, but may be easily and quickly released from a holder such as that set forth in the application above mentioned.

10 With the above and other objects in view, the invention consists of certain novel features of construction that will be hereinafter more fully described and particularly pointed out in the appended claims.

15 In the accompanying drawing:

Figure 1 is a vertical sectional view through a retainer and showing a punch embodying my invention in operative position in said retainer;

20 Figure 2 is a detail view of the punch;

Figure 3 is a sectional view taken on the line 3—3 of Figure 2.

Referring now to the drawings, 1 is a punch having suitable shank and work engaging head portions, 2 and 3 respectively, 4 is a retainer body having a bore 5 for receiving the shank 2 of the punch and having a pocket or recess 6 at one side of the bore containing means for retaining the shank 2 in the bore 5.

25 As shown the means in the recess 6 in the holder 4 for retaining the punch shank 2 in the bore 5 comprises a lever 14 having a rounded or spherical end portion 15 pivotally engaging a rounded portion 16 of the recess 6 and preferably having an arcuate end portion 17 engageable with the longitudinally curved base 18 of an arcuate recess 19 in one side of the punch shank 2, a coil spring 20 engaging the lever 14 and normally holding the arcu-

30 ate end portion 17 thereof in the bore 5, and a shell 21 that constitutes a housing for the spring 20 and for the spherical end portion 15 of the lever and that prevents accidental displacement of the said spherical portion 15 from the rounded portion 16 of the recess 6.

The rounded portion 16 of the recess 6 is concentric with the center 22 of the spherical portion 15 and constitutes a backer or bearing for said spherical portion in all positions of pivotal adjustment of the lever. In fact, the 50 arrangement of the spherical end rounded portions 15 and 16 respectively is such that the spherical portion 15 slidably engages the rounded portion 16, and the outer free end of the lever is so fashioned with respect to the 55 base 18 of the recess 19 in the punch that the longitudinal thrust imparted to the lever when the free end thereof is engaged with the base 18 of said recess is transmitted directly from the spherical portion 15 to the rounded 60 portion 16. Therefore, as the lever swings in an arc the spherical portion 15 will transmit this thrust or load to correspondingly different points of the rounded portion 16. Moreover, due to this arrangement of the spherical 65 and rounded portions, the outer free end of the lever may be so fashioned that the punch will be effectively held by the lever acting as a prop or brace and may be easily and quickly released from the lever and removed from the body 4 as will be hereinafter more fully set forth.

70 Preferably the arcuate end portion 17 of the lever is eccentric to the center 22, said arcuate end portion 17 being concentric with an eccentric point 22' of the spherical portion 15. Moreover, when the parts are in the position illustrated in Figure 1, the longitudinally curved base 18 of the recess 19 in the shank 2 is also eccentric to the center 22, 75 but concentric with the arcuate end portion 17, the dotted line in Figure 1 representing an arc concentric with the center 22. As shown the recess 19 is adjacent to the upper end of the shank 5, hence when the arcuate 80 end portion 17 engages the base 18 of the recess in the tool shank 2, a propping or bracing action in contradistinction to a wedging action, and an area contact instead of a point contact is obtained. Likewise when the 85

lever is raised the end portion 17 is released from the base 18 and is therefore readily removable from the recess.

In use, the arcuate end portion 17 will normally be held by the spring 20 in the bore 5 but when the shank 2 of the punch is inserted in the bore 5, the arcuate end portion 17 of the lever will automatically engage the base 18 of the recess 19 in the shank 2 and will effectively hold the punch in assembled position. However, any suitable means such as the shank 50 of a tool 51 may be inserted through a bore 25 into the recess 6 to disengage the lever 14 from the shank 2.

15 Thus, with my construction a tool may be readily removed from a holder without the necessity of taking apart the holder or separating it from the usual backing plate 40. Moreover, a better gripping action is obtained 20 and there is no tendency of the parts to wedge.

In the preferred embodiment of my invention, the recess 19 in the shank 2 is transversely curved in arcuate form as indicated at 18A. The recess may be described as having a surface formed by the intersection of a tore with the cylindrical shank 2. In the preferred construction the tore defining the curvature of the recess has an outside diameter substantially three times the diameter 25 of the generating circle which defines the transverse curvature. The depth of the recess is preferably $\frac{1}{3}$ of the diameter of the generating circle.

30 It is desirable that the recess 19 be maintained quite accurately within certain limits of tolerance and one specific construction that has proved to have exceptional merit has a generating circle corresponding to the following formula:

$$40 \quad MC = .375 MB - .03125 \pm .008''$$

In this case the depth of the recess corresponds to the following formula:

$$45 \quad MA = .333 MC - .0104 \pm .0104''$$

In the above formulas MA represents the depth of the recess, MC the diameter of the generating circle and MB the outside diameter of the tore.

50 What I claim as my invention is:

1. A punch having a longitudinally extending groove, the surface of said groove corresponding to a tore in which the generating circle is substantially $\frac{1}{3}$ the diameter of the outside diameter of the tore, said groove having a depth approximately $\frac{1}{3}$ of the diameter of the generating circle of said tore.

60 2. A punch having a longitudinally extending groove arcuately curved both longitudinally and transversely, the diameter of the transverse curvature being substantially $\frac{1}{3}$ the diameter of the longitudinal curvature and the depth of the groove being substan-

tially $\frac{1}{3}$ the diameter of the transverse arcuate curve.

3. A punch having a longitudinally extending groove having a surface such as is formed by the intersection of a cylinder with 70 a tore in which the tore has a generating circle substantially equal to $\frac{3}{8}$ of the outside diameter of the tore minus $\frac{1}{32}$ of an inch, said groove having a depth approximately $\frac{1}{3}$ the diameter of the generating circle of said tore. 75

In testimony whereof I affix my signature.

FLOYD C. KING.
